UNITED STATES PATENT OFFICE.

CARL F. A. NEITZEL, OF CONCORDIA, KANSAS.

CAR-COUPING.

SPECIFICATION forming part of Letters Patent No. 274,645, dated March 27, 1883.

Application filed July 31, 1882. (No model.)

To all whom it may concern:

Be it known that I, CARL F. A. NEITZEL, a citizen of the United States, residing at Concordia, in the county of Cloud and State of Kansas, have invented certain new and useful improvements in Car-Couplings; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention pertains to an improvement in car-couplings, having for its object to obviate the necessity of the operator or attendant going between the cars to couple or uncouple the same, and to enable the ready coupling and uncoupling of the cars; and the invention consists of a hook with a lateral rearwardly-curved arm pivoted in a spring-fulcrum, said curved arm adapted to be acted upon by a lever, itself acted upon by the arm of a shaft hung so as to be operated by a crank controlled by a ratchet and pawl, substantially as hereinafter more fully set forth and claimed.

In the accompanying drawings, Figure 1 is a plan view, showing the action of two meeting coupling-hooks. Fig. 2 is a view of a single coupling, viewing the same from the under side; and Fig. 3 is a detailed view of the same.

In carrying out my invention I employ a hook, A, made preferably of a straight bar, with a right-angled square beak, through which is made an aperture, a, to receive an ordinary coupling-pin should it be required to use it with the common draw-bar. The coupling-hook A is cast with a lateral rearwardly-curved arm, A', the curvature of the extreme inner or rear end of said arm assuming an approximate hook shape. This arm is pivoted near the inner end of the hook to a bar or fulcrum, C, with one end encircled by a spring, b, and bearing against a shoulder thereon, and a support, c, depending from the under side of the car, and through which the said bar passes, the other end of said bar passing through and projecting beyond the front end of the buffer d. In their normal position, or when the cars

are uncoupled, the outer ends of the hook A and fulcrum or bar C diverge from each other, while the said end of the bar C stands a short distance inward from the beak of the hook. 55

D is a lever fulcrumed upon a pivot secured in a bracket, e, fastened to the under side of the bottom of the car, said lever having at one end an eye or loop, f, through which the hooked end of the coupling-hook arm A' passes, said eye or loop having a frictional roll, against which the said arm bears to lessen friction. The other end of the lever slides between and is acted upon by means of projections or studs g g, cast upon one side of a cam-arm, E, secured to a handled shaft, F, said shaft bearing in suitable brackets, h h, fastened to the end of the car. This shaft is also capable of operation at the side of the car, upon the ground, by means of the lever or handle G, and is provided 70 with a ratchet, i, with which engages a pawl, j, fulcrumed upon a plate or support, k, fastened to the platform or top of the car.

It will be noticed that when the cars are meeting preparatory to coupling, by turning 75 the hand-wheel shaft to the right, the hooks of the meeting cars will interlock or couple and the front ends of the bars C will be brought in rear of the hooks, preventing contact of the hooks with the cars, though allowed a limited 80 play by the yielding action of the springs of said bars. At the same time the ratchet of the shaft F will be engaged by the pawl j, and thus cause the holding of the hooks in a coupled position. To uncouple the cars it is obvious that it is only necessary to release the 85 pawl j, the springs b of the bars C throwing the hooks apart and the bars C away from the hooks.

I claim and desire to secure by Letters Patent— 90

1. In a car-coupling, the coupling-hook having an arm and the spring-bar, said arm being pivoted to said bar, and thence extending to the opposite side thereof and curved inwardly, 95 in combination with mechanism to adapt the hook to interlock with the meeting hook, and to cause the bar to adjust itself in rear of the interlocking coupling-hook, substantially as and for the purpose specified.

2. In a car-coupling, the coupling-hook having a lateral curved arm and a spring-bar, said 100

arm being pivoted to said bar, in combination with the lever attached to the heel of the curved arm and actuated by the handle or hand-wheel shaft, said shaft acting upon the coupling-hook arm, and the intermediate mechanism, substantially as and for the purpose set forth.

3. In a car-coupling, the coupling-hook having a lateral rearward-curved arm, said arm being pivoted to a spring-bar, in combination with the lever, with one end acting upon the

said coupling-hook arm, and its other end actuated by an arm upon the lever, which turns with the shaft of the hand-wheel, said shaft having a ratchet engaged by a pawl pivoted to a fixed point, substantially as and for the purpose set forth.

CARL F. A. NEITZEL.
